3 Claims. (Cl. 252—361)

1

This invention relates to a method and apparatus for eliminating foaming conditions in steam boilers.

Foaming of boiler water is not, as commonly thought, equivalent to an accumulation of foam on top of the surface of the boiler water. When steam is rapidly withdrawn from a boiler with resultant foaming, there is no water surface within the boiler correlated with the water level indicated in the conventional water glass attached to the boiler. In other words, there is no sharp line of demarcation between "solid water" and foam in a boiler during rapid steam withdrawal.

The foaming of boiler water is actually a rapid expansion of the water in the steam generating area of the boiler brought about by myriads of small steam bubbles that do not increase appreciably in size and do not coalesce to form large bubbles. As a consequence, the entire volume of water in the steam generating area is expanded by myriads of rising small steam bubbles until the thus formed so-called "light water" may fill the steam space and become entrained with the steam leaving the boiler. Thus, foaming is actually due to the rapid formation of very large numbers of small steam bubbles that rise through the water without coalescing and without growing appreciably in size.

I have now found that foaming in boiler water may be prevented by inducing formation in the steam generating region of a relatively small number of relatively large bubbles rather than a relatively large number of relatively small bubbles. I have further found that such formation of relatively few large bubbles can be induced by establishing in the boiler water, at or near the boiler area utilized for heat transfer to the boiler water, a layer of superheated water of substantial depth or thickness and providing nuclei for steam generation in said layer adjacently or on the heat transfer surface. Large steam bubbles are formed in limited number more or less exclusively at these nuclei and rise through the layer of superheated water, and during such rise act as additional nuclei for additional steam generation so that superheated water is rapidly evaporated into such bubbles. As a result, the bubbles grow in size while rising through the superheated layer of water. Since nuclei for steam generation are provided in the superheated region of the boiler, steam generation occurs preferentially at these nuclei and into the bubbles rising from the nuclei, with consequent formation of few but large bubbles rather than a large number of small bubbles. Such boiling will prevent any abnormal

2

superheating of the body of boiler water and therefore minimizes the formation of numerous steam-generating nuclei in the boiler water, so that no foam formation will occur.

5 The nuclei for steam generation provided according to the present invention in the superheated region of the boiler water preferably takes the form of one or more gas-water interfaces established at one or more localities, so that steam generation will occur into one or more gas pockets. The gas pockets may be established intermittently or more or less permanently. For instance, I may provide adjacently the heat transfer surface one or more inverted cup-like structures adapted to form steam pockets, or I may drop into the boiler a small number of "ebullators" (more or less irregularly configurated solid objects adapted to form air or steam pockets, or otherwise capable of acting as nuclei for the generation of steam), 10 for instance, of spherical form and provided with indentations over all or part of their surfaces. I can also release or generate gases such as inert gases, nitrogen or hydrogen in the superheated boiler water region, or provide electrical heating means disposed in the superheated region to generate steam bubbles herein. Further, mechanically, electrically, or magnetically operated vibrators, means for forcing a stream of water against a baffling surface, or other cavitating means may 15 be employed to establish internal cavities in the boiler region containing superheated water.

20 To confine the generation of steam to the nuclei provided as disclosed, I can incorporate with the boiler water hydrophilic substances, such as hydrophilic colloidal matter, that render the walls of the boiler as well as solid particles suspended or dispersed therein hydrophilic so as to lessen the capacity of the boiler walls or the solid particles for acting as nuclei for steam generation. 25 Such substances include tannins, alginates, gum arabic, lignin sulfonates and synthetic hydrophilic colloids. Boiler water containing surface tension-reducing agents, such as wetting agents, of course, inherently tend to foam, but when such tension-reducing agents, in particular, wetting agents, are employed as disclosed in the present application, these substances have the surprising effect of inhibiting foaming completely.

30 It is, therefore, an important object of the present invention to provide improved methods and apparatus for inhibiting foaming in boiler water having a natural tendency to foam.

35 Another important object of the present invention is to provide methods and apparatus for in-

hibiting foaming in boiler water involving the establishment of a layer of superheated water in a body of boiler water and selectively inducing generation of steam bubbles at or near the bottom of said layer whereby evaporation is effected principally into steam bubbles with the result that the steam bubbles grow into large bubbles as they rise through the layer of superheated water.

A further important object of the present invention is to provide methods and apparatus for preventing foaming in boiler water involving the establishment of a layer of superheated water of substantial depth in the body of boiler water, providing one or more gas pockets at or near the bottom of said layer of superheated water, and affecting evaporation into said gas pockets with resultant formation of steam bubbles that grow into large size on rising through the layer of superheated water after breaking away from the gas-water interface.

Other and further objects and features of the present invention will become apparent from the following description and appended claims as well as from the attached drawings which show, diagrammatically and by way of examples, several types of apparatus and methods according to the present invention. More particularly:

Figure 1 is a fragmentary vertical longitudinal cross-sectional view, with parts shown in elevation, through a locomotive boiler equipped with a device according to the present invention;

Figure 2 is a front elevation of the structure shown in Figure 1;

Figure 3 is a greatly enlarged transverse cross-sectional view through the foam inhibiting device in the locomotive boiler of Figure 1;

Figure 4 is a greatly enlarged fragmentary side elevation of the device shown in Figure 3;

Figure 5 is a greatly enlarged transverse vertical cross-sectional view through another foam inhibiting device capable of being substituted for that shown in Figures 3 and 4;

Figure 6 is a greatly enlarged fragmentary side elevational view of the device of Figure 5;

Figure 7 is a view similar to Figure 2 showing a device similar to that shown in Figures 3 and 4 disposed in the locomotive boiler in a slightly different manner;

Figure 8 is a vertical transverse cross-sectional view through a locomotive boiler similar to the boiler shown in Figure 1, but equipped with another foam inhibiting device according to the present invention, the view of Figure 8 being taken along the line VIII—VIII of Figure 1;

Figure 9 is a fragmentary horizontal longitudinal cross-sectional view through a locomotive boiler similar to that shown in Figure 1 but equipped with another foam inhibiting device according to the present invention, the view of Figure 9 being taken along the line IX—IX of Figure 1;

Figure 10 is an end elevational view of the structure shown in Figure 9;

Figure 11 is a greatly enlarged vertical cross-sectional view through one of the foam inhibiting devices shown in Figures 9 and 10;

Figure 12 is an end elevation similar to Figure 2 showing a locomotive boiler provided with still another foam inhibiting device according to the present invention;

Figure 13 is a fragmentary horizontal cross-sectional view of the boiler of Figure 12 similar to the view of Figure 9;

Figure 14 is a greatly enlarged fragmentary

vertical cross-sectional view taken along the line XIV—XIV of Figure 12;

Figure 15 is a vertical cross-sectional view through a stationary boiler equipped with foam inhibiting devices according to the present invention;

Figure 16 is a greatly enlarged cross-sectional view through one of the foam inhibiting devices of Figure 15;

Figure 17 is a greatly enlarged fragmentary cross-sectional view through one of the foam inhibiting devices and through the crown sheet of the locomotive boiler shown in Figures 18 and 19;

Figure 18 is a view similar to Figure 2 showing a locomotive boiler equipped with still another foam inhibiting device according to the present invention;

Figure 19 is a view similar to Figure 9 showing the boiler of Figure 18;

Figure 20 is a view similar to Figure 2 showing a locomotive boiler equipped with still another foam inhibiting device according to the present invention;

Figure 21 is a view similar to Figure 9 showing the boiler of Figure 20 in horizontal cross section;

Figure 22 is a view similar to Figure 2 showing a locomotive boiler equipped with still another foam inhibiting device according to the present invention;

Figure 23 is a view similar to Figure 9 showing the boiler of Figure 22 in horizontal cross section;

Figure 24 is a side elevational view, with parts broken away, of the tube and drum system of a conventional Stirling boiler equipped with a foam inhibiting device according to the present invention;

Figure 25 is a greatly enlarged fragmentary longitudinal cross-sectional view through one of the tubes of the boiler of Figure 24; and

Figure 26 is a greatly enlarged cross-sectional view, with parts shown in elevation, of the foam inhibiting devices shown in Figures 24 and 25.

The locomotive boilers shown in Figures 1, 2, 7, 8, 9, 10, 12, 13, 18, 19, 20, 21, 22 and 23 are of conventional construction, apart from the foam inhibiting devices illustrated, and include a tubular boiler generally indicated by the reference numeral 10 having a conventional arrangement of tubes 13 and provided with a dome 14 having the usual dry pipe 15. A portion 16 of the firebox of the boiler has been illustrated in certain figures, and also the drainage outlet 17 in the lower portion of the boiler. The crown sheet and stay bolts associated with the boilers are indicated, respectively, by the reference numerals 18 and 19. The side sheets are shown at 20. The water level is indicated by a broken line 21. Since these various features are uniform throughout the different figures, the same reference numerals have been used in all the figures showing locomotive boilers.

Referring now to Figures 1 and 2, it will be noted that a plurality of bars or rods 25 are disposed on the crown sheet 18 to rest thereon between the stay bolts 19 lengthwise of the boiler. As best shown in Figures 3 and 4, the rods 25 are provided on their surfaces with a plurality of spaced conical indentations 26. These indentations preferably have at least their inner ends of capillary size and serve to establish immediately above the crown sheet a plurality of steam or air pockets that act as nuclei for the generation of steam bubbles. These rods 25 are preferably spaced from the crown sheet (say, by about one-

quarter inch) and from each other by collars or washers 27. The crown sheet 18 is maintained hot enough to establish thereabove a layer of superheated water of substantial depth, preferably deeper than the thickness of the rods 25. The steam bubbles preferentially generated with the indentations 26 as nuclei rise through this superheated layer of water and in so rising serve to promote evaporation of additional steam into the steam bubbles, with resultant growth of the latter. The steam bubbles rising to the water level 21 are relatively few in number, due to the restricted number of indentations 26, and are also rather large due to growth by evaporation of additional steam thereinto. These bubbles therefore do not cause foaming.

In place of the rods 25, I may also utilize rods 30 illustrated in Figures 5 and 6 and characterized by longitudinal grooves 31 that act as nuclei for the generation of steam similarly to the indentations 26 of the rods 25. The rods 30 are spaced from the crown sheet and from each other by collars or washers 32. It will be noted that in both types of rods or bars, the indentations 26 as well as the grooves 31 act as nuclei for the generation of steam by providing spaces or pockets wherein air or steam may accumulate to define a gas-water interface.

In Figure 7, I have illustrated a locomotive boiler provided with bars 35 constructed identically as the bars 25, except for the omission of any collars or washers. Instead of being laid on the crown sheet, as are the bars 25, the bars 35 are held a fraction of an inch above the crown sheet 18 by suitable means, such as clamps 36 attached to the lower ends of the stay bolts 19. The bars 35 are indented similarly to the bars 25 and perform the same function. It will be noted that the bars 35 provide gas pockets at the bottom of the superheated water layer immediately above the crown sheet where the rate of heat transfer is rapid.

In Figure 8, other means for establishing gas-water interfaces in a superheated region of a body of boiler water are shown. There the two topmost rows of boiler tubes 13 are provided on their sides with longitudinal downwardly directed fins 40 each defining in combination with the boiler tube a narrow steam space adapted to function similarly to the indentations or grooves in the bars 25, 30 and 35.

In Figures 9, 10 and 11 I have shown still other means for establishing gas pockets in a superheated layer of boiler water that take the form of inverted cup-like members 45. Certain of these cup-like members 45 are held a fraction of an inch or so above the crown sheet 18 by means of bars 46 extending lengthwise of the boiler between the stay bolts 19 with their ends attached to transverse bars 47 which, in turn, have their ends affixed to the inside of the boiler. Other cup-shaped members 45 are suspended along the upper portion of the side sheets 20 by means of bars 48 extending lengthwise of the boiler and having their ends affixed to transverse bars 49 having their ends attached to the side sheet and to the sides of the boiler. The inverted cup-like structures 45 are adapted to hold air or steam, and evaporation takes place into the pockets defined by these cup-like structures that serve as nuclei for steam generation. The steam bubbles break off from the lower edges of the cup-like structures 45 and rise through a layer of super-

heated water established immediately above the crown sheet 18 and at the sides of the upper parts of the side sheet 20, with the result disclosed hereinabove.

5 It is also possible, as shown in Figures 12, 13 and 14, to provide a crown sheet 18 formed with a plurality of downwardly directed conical indentations 50 preferably terminating in capillary spaces that will serve as nuclei for steam generation due to capillary retention of air or steam, and to bring about particularly effective heat transfer into the spaces defined by the indentations 50 by reason of the increased surface available for heat transfer. Steam generation tends to be localized at the indentations 50, so that relatively few steam bubbles rising therethrough and growing due to evaporation while passing through the superheated layer of water immediately above the crown sheet will not induce foaming.

A gas-water interface may also be provided by means shown in Figures 17, 18 and 19, and including a series of tubes 60 disposed lengthwise 25 of the boiler, over the crown sheet 18 and along the side sheets 20 and provided with spaced bottom apertures 61. The tubes 60 may suitably be supported by legs 62. A gas such as hydrogen, nitrogen or other gas insoluble in water, is fed to the tubes 60 through a branched tube 63 connected to one set of ends of the tubes 60. The other ends of tubes 60 are preferably closed. The gas may be supplied to the tube 63 from any suitable source (not shown) such as a tank carried on the locomotive outside the boiler. The tubes 60 are preferably quite small having, for instance, a diameter of one-quarter inch, and the apertures 61 may have a diameter such as one-thirty-second inch. The rate of flow of gas 30 through the tube 63 into the tubes 60 is preferably such as to permit the escape of gas through the apertures 61. In this case, the rising gas bubbles provide for the evaporation of steam into the gas bubbles as the latter rise through the superheated layers of water immediately above the crown sheet 18 and along upper parts of the side sheets. The gas bubbles will, therefore, grow in size during their passage through the layer of superheated water, so that the large bubbles breaking on the surface of the boiler 35 water will not induce foaming.

In Figures 20 and 21, I have shown still other means for providing gas-water interfaces in a superheated region of a body of boiler water. As shown, pairs of positive electrodes 65 and negative electrodes 66 are disposed lengthwise 55 of the locomotive boiler a fraction of an inch above the crown sheet 18 between the stay bolts 19. The anodes 65 are energized by means of a conductor or lead wire 67 entering into the boiler through a plug of insulating material 68. The cathodes 66 are likewise energized by means of a lead wire 69 entering into the boiler through an insulating plug 70. Insulating clamps 71 hold the electrodes spaced from one another, from the crown sheet, and from the stay bolts. The bubbles of oxygen and hydrogen rising from the anodes 65 and the cathodes 66 grow in size 60 as they rise through the layer of superheated water immediately above the crown sheet due to evaporation into the bubbles. The relatively few rather large steam containing bubbles thus formed do not induce foaming.

Figures 22 and 23 show other means for providing gas-water interfaces in a superheated

region of a body of boiler water. In these figures, I have shown a resistance wire 75, such as Nichrome, disposed over the crown sheet 18, a fraction of an inch thereabove lengthwise of the boiler between stay bolts 19 and attached thereto by means of insulating clamps 16. This electrical resistor 75 is energized by means of a lead wire 77 entering and coming out from the boiler through an electrically insulated plug 78. Steam generated around the heating element 75 provides a gas-water interface from which steam bubbles break away and rise through a superheated layer of boiler water. During such rise, the steam bubbles increase in size due to evaporation into the steam bubbles from the superheated water. Relatively few but large steam bubbles are thus formed that do not induce foaming.

Any of the means for establishing gas-water interfaces in the vicinity of a locomotive firebox illustrated in Figures 1 to 14 and 17 to 23 may also be provided in the vicinity of the boiler tubes of a locomotive, if desired or necessary to more completely inhibit foaming.

In Figure 15 I have shown a stationary vertical boiler 80 set in brick work or the like 81 providing a fire box 82 below the boiler having a grate 83 adapted to hold solid fuel. Flues 84 are formed in the brick work around the lower sides of the boiler, which is provided with a steam pipe 85. Means for preventing foaming take the form of a plurality of small spheres or pellets or relatively small bodies 90 (see Figure 16) provided on their surface with spaced minute indentations 91 preferably terminating inwardly in capillary spaces. These pellets 90 may be dropped into the boiler 80 so as to rest on the bottom of the boiler. The minute indentations 91 on the "ebullators" 90 serve to prevent foaming by the generation of large steam bubbles in the manner explained hereinabove.

Any of the means for establishing gas-water interfaces described in connection with locomotive-boilers and illustrated in Figures 1 to 14 and 17 to 23 may be employed in a stationary boiler to minimize or prevent foaming.

In Figures 24 and 25 I have shown the tube and drum system of a conventional Stirling type steam boiler. The feed water tubes are indicated by the reference numeral 100, the tubes wherein steam rises by the reference numeral 101, and the drums by the reference numeral 102. In the tubes are disposed relatively deep inverted cup-like structures 105 (see Figure 26) having their bottoms pierced as at 106 to receive and fit tightly over wires 107 on which a plurality of such cup-like members 105 are threaded. Collars 108 on the wire 107 abut the two sides of the bottoms of the members 105, to hold the members 105 on the wire and to insure complete closure and sealing of the apertures 106. Each tube 100 is provided with a wire 107 having a plurality of inverted cup-like structures 105 attached thereto. The upper end of the wire projects into an upper drum and is there attached to suitable means, such as a cross bar 108, while the lower ends project into the lower drum for attachment to a cross bar 109. As shown in Figure 25, the inverted cup-like structures are deep enough to provide gas pockets even at the bends or curves of the tubes 100.

The inverted cup-like structures 105 serve as nuclei for steam generation and prevent spasmodic, eruptive boiling within the tubes 100 which otherwise would occur when the tubes 100

are filled with superheated water and resulting columns of superheated water are suddenly displaced upwardly by the formation in or entrance of steam bubbles into said tubes.

It will thus be seen that I have provided a method for eliminating foaming in the generation of steam from water including the steps of transmitting heat to the water at such rate as to establish and maintain in the body of water being heated a definite layer of superheated steam of quite substantial depth and also providing nuclei for preferential steam generation at or near the bottom of the layer of superheated water. These nuclei preferably provide smaller or larger gas pockets defining gas-water interfaces. Steam evaporates into the gas pockets, with the result that steam containing bubbles break away from the gas-water interface and rise through the body of boiler water. During their rise through the superheated layer of boiler water, evaporation from the superheated water into the rising bubbles takes place, so that the latter grow in size, with the result that relatively few but relatively large steam-containing bubbles rise to the surface of the water and break there.

In order to eliminate or reduce the formation of steam bubbles at other localities than the above-mentioned nuclei, I may, and preferably do, incorporate with the water a hydrophilic substance, in particular, a hydrophilic colloid such as sodium alginate, tannin, lignin, sulfonate, redwood bark dust extract, gum arabic, or the like. These hydrophilic materials serve to induce more complete wetting of the boiler walls and of any solid particles suspended therein, so that the boiler walls and such suspended particles do not tend to act as nuclei for the generation of steam. Similar results may be obtained by incorporation with the boiler water of surface-tension reducing substances such as ordinary soaps, "Aerosol OT" (dioctyl ester of sodium sulfosuccinic acid), "Aresket" (monobutyl diphenol sodium monosulfonate), "Igepon T" ($C_{17}H_{33}CONHC_2H_4SO_3Na$) or the like. When wetting agents such as those disclosed are added to water in small amounts, such as less than 500 parts per million, their effect is principally to reduce directly the surface tension of the water. When added in larger amounts, such wetting agents are believed to form micelles that are highly hydrophilic and tend to absorb or capture hydrophobic materials dispersed or suspended in the boiler water, such as hydrocarbon oils, thereby reducing or eliminating undesired nuclei for steam generation. In such higher concentrations, where micelle formation is believed to take place, the surface activity of the wetting agent is believed to decrease.

In brief, the action of the mechanical devices illustrated and described hereinabove can be and preferably is reinforced by incorporating with boiler water surface tension reducing agents, in particular, wetting agents, so that the water will wet the boiler walls as well as any hydrophobic solid or liquid particles suspended or dispersed therein, with the result that the tendency for any part of the boiler wall or for any solid or liquid matter suspended or dispersed in the boiler water to function as nuclei for steam generation is reduced or eliminated. Many boiler waters have a natural tendency to foam, due to a content of surface tension reducing agents, which inherently tend to produce foaming. The methods of the present invention are particularly applicable to the prevention of foaming in such boiler waters.

When boiler water contains a relatively large amount of surface tension reducing agents, either due to accumulation of such agents (derived from the feed water or from lubricating oil or from contamination) or due to deliberate addition of surface tension reducing agents, the whole body of boiler water may become superheated, since then nuclei for steam generation such as suspended solid particles or irregular parts of the boiler surface have been rendered hydrophilic and hence inactivated as nuclei for steam generation. The gas-water interfaces provided according to the present invention are particularly adapted to function as nuclei for steam generation in such wholly superheated waters, since the gas-water interfaces are not inactivated by hydrophilic agents as are the surfaces of suspended solid particles or parts of the boiler walls. It should further be noted that when the whole body of boiler water has become superheated, then even somewhat hydrophilic solid particles or areas of the boiler walls may function as nuclei for steam generation, with the resultant formation of a large number of small bubbles and consequent foaming. However, the provision of gas-water interfaces according to the present invention will lessen substantially the tendency of the whole body of boiler water to become superheated, so that the tendency of the boiler water to foam is reduced or eliminated.

In other words, the gas-water interfaces provided according to the present invention and the means above disclosed for establishing or generating such gas-water interfaces are particularly adapted to prevent or reduce foaming in boiler waters that are or have been made more hydrophilic due to accumulation therein or addition thereto of surface tension reducing agents or agents that otherwise tend to eliminate steam generating nuclei normally functioning in the boiler water. Such hydrophilic boiler waters as well as boiler waters devoid of nuclei for steam generation have a natural tendency to foam which is reduced or eliminated by the means described hereinabove for establishing gas-water interfaces in the boiler water.

As illustrated by specific examples described hereinabove, the means disclosed in the present invention for establishing nuclei for preferential localized steam generation can be provided in many forms, including means defining small preferably capillary spaces either in the water side of the heat transmitting boiler wall or in other structures in the immediate vicinity of the heat-transmitting boiler walls, independently heated means disposed in the boiler in the immediate vicinity of the heat-transmitting boiler walls, means for generating or releasing or exposing gases insoluble in water in the boiler in the immediate vicinity of the heat-transmitting boiler walls, or the like.

It should be understood that many details of construction, composition, and method may be varied within a wide range without departing from the principles of this invention and without sacrificing the advantages disclosed hereinabove, and it is, therefore, not my purpose to limit the patent granted on this invention otherwise than necessitated by the scope of the appended claims.

I claim as my invention:

1. For the prevention of foaming in a steam boiler having a boiler wall part utilized for heat transfer to a body of boiler water contained in said boiler, the combination with said boiler wall part of a plurality of bars disposed in the immediate vicinity of said boiler wall part and formed with indentations capable of forming gas pockets in a layer of superheated water established and maintained immediately above said boiler wall part, said gas pockets being adapted to function as nuclei for the generation of steam bubbles which on rising through said layer of superheated water will provide for the evaporation of additional steam.
2. In a steam boiler having a boiler wall part utilized for heat transfer to a body of water contained in said boiler, the combination with said boiler wall of a plurality of bars disposed in the immediate vicinity of said boiler wall part, said bars being formed with longitudinal grooves capable of forming gas pockets in a layer of superheated water established and maintained immediately above said boiler wall part, said gas pockets being adapted to function as nuclei for the generation of steam bubbles which on rising through said layer of superheated water will provide for the evaporation of additional steam.
3. In a steam boiler having a boiler wall part utilized for heat transfer to a body of boiler water contained in said boiler, the combination with said boiler wall part of a plurality of bars disposed in the immediate vicinity of said boiler wall part, said bars being formed with spaced conical indentations capable of forming gas pockets in a layer of superheated water established and maintained immediately above said boiler wall part, said gas pockets being adapted to function as nuclei for the generation of steam bubbles which on rising through said layer of superheated water will provide for the evaporation of additional steam.
